(57) **CLAIM**

The ornamental design for a multi-rotor aircraft, as shown and described.

DESCRIPTION

FIG. 1 is a perspective view of a multi-rotor aircraft showing our design.

FIG. 2 is a top plan view of the multi-rotor aircraft of FIG. 1.

FIG. 3 is a bottom plan view of the multi-rotor aircraft of FIG. 1.

FIG. 4 is a front elevational view of the multi-rotor aircraft of FIG. 1.

FIG. 5 is a rear elevational view of the multi-rotor aircraft of FIG. 1.

FIG. 6 is a right side elevational view of the multi-rotor aircraft of FIG. 1; and,

FIG. 7 is a left side elevational view of the multi-rotor aircraft of FIG. 1.

The broken lines of FIG. 3 illustrate a portion of the multi-rotor aircraft that forms no part of the claimed design.
